UNITED STATES PATENT OFFICE.

WASHINGTON I. LUDLOW, OF CLEVELAND, OHIO, ASSIGNOR, BY MESNE ASSIGNMENTS, TO THE LUDLOW TYPOGRAPH COMPANY, OF PITTSBURG, PENNSYLVANIA, A CORPORATION OF MAINE.

TYPOGRAPH.

No. 856,539.

Specification of Letters Patent.

Patented June 11, 1907.

Application filed January 27, 1905. Serial No. 242,897.

To all whom it may concern:

Be it known that I, WASHINGTON I. LUDLOW, a citizen of the United States, and a resident of Cleveland, county of Cuyahoga, State of Ohio, have invented certain new and useful Improvements in Typographs, of which I hereby declare the following to be a full, clear, and exact description, such as will enable others skilled in the art to which it appertains to make and use the same.

My invention relates to improvements in typographs or mechanism for assembling matrices representing characters for printing, before a casting box, to form slugs or bars comprising a line of characters of the width of a column of printed matter, and the objects of the invention are to simplify the mechanism required in the various operations of handling the several matrices, conveying them to their respective positions, alining and justifying them and returning them to their original stations without mixing or confusing the numerous parts.

My invention consists in the various devices, the combination and arrangement of parts and construction of the several details as hereinafter described, shown in the accompanying drawings, and specifically pointed out in the claims.

In the accompanying drawings, Figure 1 is a plan view of the entire device, showing the composer closed after assembling the matrix bars and locked to aline them; Fig. 2 is a longitudinal section of the same on line $x-x$; Fig. 3 is a central longitudinal section of the same through the composer; Fig. 4 is an enlarged plan of the composer and trough containing the matrices showing a portion of the bed of the machine, on which the composer rests; Fig. 5 is an enlarged view of the opening in the top of the machine bed showing the matrices arranged to compose a line of type over the casting slot, and some of the matrices arranged to justify the line. This view also shows a sliding detent adapted to adjust the width of the printed column; Fig. 6 is a perspective view of the composer detached from the other parts; Fig. 7 is a central transverse section of the same; Fig. 8 is an enlarged transverse section of the machine bed, showing the composer and matrices in section and the detent which adjusts the

width of column; Fig. 9 is a perspective view of a tapered matrix bar; Fig. 10 is an enlarged plan view of one end thereof; Fig. 55 11 is a perspective view of a straight matrix bar having the pointed ends; Fig. 12 and 13 are enlarged views of upper and lower sides of one end thereof respectively; Fig. 14 is a plan view (somewhat enlarged from Fig. 1) 60 showing the composer and matrix bars arranged to form a line of type above the casting slot, the detent and retaining spring for loose matrices; Fig. 15 is an enlarged central portion of Fig. 3 showing the mold slot, matrix bar, and composer in their proper relation when a line of type is cast. Fig. 16 is a perspective view of the completed slug cast by the machine.

In these figures, 1 is the frame or bed on which the devices are mounted, which accomplish my desired results; 2 is a rectangular opening in the cover thereof; 3 is a trough or receptacle which extends centrally through the entire length of the bed plate and in which are placed the matrix bars 4, in the lower face or edge of these matrix bars are impressed or cut the matrices 5 of the characters which form the type, and centrally across the bottom of this trough is cut the slot 6 in which the nozzle 7 of the mold or casting box is inserted to form the slug, the matrices being so arranged in the bars that those in adjacent bars will form a line registering with the nozzle of the mold box, so that a line of type cast therefrom will compose a line suitable for printing of the width of the column. The trough 3 in which these bars lie extends longitudinally across the frame, and the bars are provided with projecting pins 8 upon their upper faces which stand upright so as to be grasped by the hand, and are placed one in the center of each bar so that when the bars are manually thrown to the right or left the pins will serve as stops 95 for the bars against the end walls 9 of the central opening. This opening is of such a length that when the pins are in engagement with either end thereof, one-half of each bar will be exposed to sight, and the other half 100 will be covered by the upper plate or cover 10 of the frame.

As many matrix bars will be required as there may be characters in the printed line,

and I employ a number more in addition thereto which are used for justifying the line and for other purposes as will be hereafter more clearly brought out in the description.

- 5 Between these bars and the upper plate 10 of the bed is the rectangular composer frame 11, which is long enough to coincide with the inner edges of the opening 2 at its ends, and wide enough to include the composer 12 between its sides and to afford free transverse movement for the composer across the opening 2 and the matrix bars 4 exposed therein. This frame is moved freely by means of racks 13, gears 14, and shaft 15 with a milled head.
- 5 The composer is provided with as many teeth 16, and characters printed or exhibited on them as there are characters upon the matrix bars. The characters on the teeth are to be read in unison with the characters on the matrix bars, and serve as guides to the relative positions of the pins on the bars which are inclosed in the composer slots when the bars are assembled. This composer constructed as shown in Fig. 6 is carried by the frame 11 and moves transversely of the bed or at right angles to the path of movement of the matrix bars.

The pins on the matrix bars are manually brought into engagement with the slots in the composer one at a time, and to accomplish this most conveniently a number of these pins are held between the thumb and first finger of the right hand while the composer is brought down across the bars by means of the milled head 18 upon the gear shaft 15, which is grasped by the fingers of the left hand and slowly rotated as each pin is inserted by the right hand in the proper slot of the composer frame. To make this operation clear it will be observed that on each bar is placed the entire alphabet and such punctuation marks and other characters as may at any time be required to form a printed line. It is necessary in order to form the line of characters over the slot of the casting box that the required matrices on the adjacent bars should be brought in succession over the casting slot 6 which lies under the opening S between the central teeth of the composer so that when the bars are placed in position the word or characters on the upper edges of the bars in the central slot between the two central teeth can be clearly read, as shown in Fig. 14, where the phrase "The Commissioner of Patents" has been composed of the bars, and all is ready to cast the slug from the matrices on their under surfaces.

In order to bring each bar into position so that the pin thereon will engage one of the slots of the composer frame and the required character will be under the central tooth above the mold slot, each tooth is provided with a character on its upper surface where it can be read by the eye and the pin is placed in the adjacent slot to the right of the tooth,

provided with the character required. Thus if the letter A is to be cast, the pin on one of the bars is placed in the slot to the right of the tooth A, when it will be found that the matrix A on the lower side of the bar is directly under the central opening in the composer. This necessarily must be so since there are the same number of characters on the teeth that there are on the bars and they are placed in exactly the same order and equally distant one from another. One of the central teeth of the composer 12 is blank or without a character for the reason that the central slot being over the mold slot, it would not be possible to place a pin of a matrix bar therein when forming a word for the reason that all the bars are blank underneath the pin. When all the bars are in place that are required to form a line, the composer is pushed entirely across the opening 2 by means of the racks and pinions described, and the points of the teeth of the composer frame 12 are inserted in guide slots 20 in the wall of the opposite side of the opening, which serve to keep the teeth rigid and make the alignment secure so that there will be no variation in the positions of the letters or characters but they assume their proper position in the line of type. To serve as a temporary assistance to keep the pins 8 in the slots between the teeth, the points are slightly barbed or projected into the slot on either side at 22, these projections serving as slight detents to hold the pins from slipping out but presenting no obstruction to slipping easily in. Guide lags 100 23 upon the frame of the composer move in slots 24 in the lower plate of the main frame and keep the composer in perfect alignment with the slot of the casting box and slug. See Figs. 4, 6, and 7.

In order to "justify" the series of matrix bars and to tighten them closely together so as to leave no spaces for liquid metal to pass through between them, when they are in position over the mold slot, they are wedged together securely before the cast is taken. The matrix bars are all duplicates and are finely tapered at each end at 28. A portion of the bars are employed to form the line of type, and a portion of the bars are brought together, end to end, between the words and their pointed ends are wedged together to justify the line and to form the blank spaces. These bars have blank surfaces beneath their pointed ends and beneath the central pins so that these blank surfaces can be used as justifying spaces or for filling the whole or any portion of a blank space.

A sliding detent consisting of a bar 27 in the front of the bed plate is pushed inward 125 and acts as a gage to fix the width of the column as seen in Figs. 1, 4, 5, 8, and 14 and the line is justified by means of the wedging ends of the matrices which form the spaces and which force the matrices against the detent 130

on one side and the wall of the trough on the other. These matrix bars and wedge shaped extremities are very thin and flexible and when closed under pressure may occupy a 5 justifying space either greater or less than the width of a single bar according to the length of the lap or engagement. The detent is provided with the spring 29 which forces a keeper 30 into a notch 31 in the bed 10 plate when the detent is adjusted to fix the width of the column.

In order that it may not be necessary to remove superfluous matrices from the trough when a line is formed, they are perforated at 15 each end at 32 so that the detent bar 27 may pass through them as shown in Fig. 5 and a strong spring 33 between the line of matrices and side wall of the opening keeps them closely together. This spring is shown of 20 bow shape, but the shape is not important to the invention. This spring also serves to keep the bars in close contact during the operation of forming the line so that they will more readily keep their places until locked together by the detent and justified.

The manner in which a line of matrices forming words is set up and justified to permit of casting a slug or line of type therefrom may be described as follows: The composer is 25 first thrown to the back of the opening 2 by means of the milled head pinions and racks, thus disclosing the matrix bars, the pins of which may now be thrown back to one or both ends of this opening, the end walls of 30 which will serve as stops to prevent their further movement and which serve to assemble them so that the pins can be readily grasped by the hand, or the pins may be assembled in a central line, between the central 35 teeth of the composer before it is thrown back. The first word is then formed one letter at a time, by placing the pin of each matrix bar in turn in the slot of the composer adjacent to the tooth having the desired 40 character or letter, thus bringing the desired character or letter over the casting slot. One word being formed two or more bars are separated by throwing in opposite directions until their wedging points slightly overlap 45 and they coact to form a space and to justify the line. The composer is brought forward from time to time to inclose the pins of the matrices, as they are placed to form words. The next words and spaces are formed in a 50 similar manner until only a slight space is left between the last bar and the detent which is to be filled by justifying the line, and the detent being adjusted to regulate the exact width of the column, the line is finally 55 justified by forcing the bars which form the spaces together until there is no opening left between the rear wall and the detent. A 60 justified line is seen in Fig. 5. The remaining bars are kept in place by running the detent bar through the openings therein, and 65

the spring 33 serves to keep them together. To obtain further pressure upon the bars, if required, a forwardly turned lug 30 on the rear bottom edge of the composer is made to engage the inner bar and by means of a sharp 70 turn on the milled head of the operating shaft at the moment of casting an additional pressure insures tightness of the joints. A further instrumentality to bring the bars and composer into true and closer alinement 75 with the casting slot during the act of casting is seen in the transverse grooves 34 upon the top of each matrix bar into which slight ridges 35 upon the central teeth of the composer enter as seen in Fig. 15, and grooves 36 80 upon the lower edges of these bars into which enter ridges 37 upon the upper edges of the casting or mold slot. In order that the ridges upon the teeth of the composer may not interfere with the freedom of movement 85 of the bars when used for justifying the upper edges of the points of these bars are cut away at 38. And the lining of the mold slot is vertically movable so that the ridges upon the edges of the slot can be lowered so that 90 the bars can slide readily in the bottom of the trough before the casting is made. The ridges on the composer teeth do not interfere when manipulating the matrix bars to bring the proper characters in line since the 95 teeth are not moved over them until they are placed.

Two forms of matrix bars are shown, one being perfectly straight with parallel sides and tapered ends, the other tapered toward 100 each end from the center and also provided with tapered ends. Upon the tapered matrices the letters and characters are arranged with the wider letters in the central portion and the narrower letters toward the narrow 105 extremities. As soon as the casting has been made from the matrices, the detent is withdrawn and the wedged bars released, the composer is then quickly drawn back by a rolling movement of the left hand upon the 110 milled head of the gear shaft, and the matrix bars are quickly placed at either side of the opening by a sweep of the hand. It is not important toward what end of the opening the bars are placed before assembling them 115 to form a line. In Fig. 4 the pins are shown in the central position, but an operator having good use of both hands could separate them, one half of the pins resting against one end of the opening, and the other half against 120 the other end of the opening. The bars which are used as spaces must be first moved to opposite ends of the opening and when wedged together their pins would be approximately in line at a slight distance from the 125 end walls of the opening as shown in Fig. 5 in order to space uniformly. The pins of the surplus bars through which the detent bar passes are seen in Fig. 5 to closely engage the 130 end walls of the opening 2 so as to make the

openings in the bars coincide. The same result however could be obtained if these bars were all moved to one side of the opening.

The advantages of this device over the complicated automatic devices heretofore employed for this purpose are obvious. In these machines, devices greatly multiplied in number and complexity are required to manipulate the large number of separate matrices, to grasp and hold them singly and collectively, conduct them singly to the mold box and re-distribute them to their original positions with such care and precision that they will not be confused or pied in the operation, and very closely and accurately fitting mechanism, liable to get out of adjustment, is indispensable to accomplish these results. Furthermore, expert mechanics must be constantly in attendance to keep the mechanism in working order. In devices of that kind the operator necessarily loses control of so many individual pieces and cannot be held responsible if anything goes wrong. In this device however all the matrices are formed in each bar, and cannot be misplaced or lost and no mechanism is required to control their movements, hence nothing approachable to the proverbial "printers pie," can result from their use, since they are all fixed in place and cannot be displaced out of their fixed order. No distributing mechanism is required since they are returned to place by a sweep of the hand, or they need not be returned to the end of the opening at all but merely gathered together at the center. This simple method of composing leaves the bars where they need no redistribution but may be quickly placed back in line. It will also be seen that no additional spacers are required, because each bar is capable of performing that function if its position requires such use.

Heretofore matrix bars have been only pointed at one end and have been held more or less securely for longitudinal movement at the other end. In this invention however, the duplicate doubly tapered extremities of each bar permit it to enter the series of bars, from either side of the casting or mold slot, and when the bars are centrally collected together over the slot for the purpose of casting a slug, they can be dispersed in either direction, which ever happens to be the most convenient, without preventing their reassembling in whatever order desired. That is they have the function of interlocking from either end and adaptability for wedging together however placed, hence perfect reversibility and greatly increased practicability and simplicity and ease of operation is obtained.

Having described my invention, what I claim as new and desire to secure by Letters Patent, is:

65 1. A matrix bar for the purpose described,

provided with a complete series of matrices, formed in one edge thereof and both ends of the bar being tapered in opposite directions, from the center.

2. A matrix bar provided with a series of 70 matrices in one edge thereof, and with transverse recesses in said edge between the matrices, the said bar being provided with oppositely tapered extremities, substantially as described.

3. In combination with a bed plate, matrix bars supported thereon, the said matrix bars being each provided with a series of matrices formed in one edge thereof, adjacent to the bed plate, and with transverse recesses 80 between the matrices, a vertically movable mold slot lining provided with ridges adapted to engage with said recesses.

4. The combination with a series of adjacent matrix bars and pins secured thereto, of 85 a composing device provided with slots arranged to receive, retain, and assemble said pins, and thereby align the adjacent matrices upon the bars, substantially as described.

5. In combination with a frame or bed 90 plate, a trough placed therein, a series of matrix bars arranged longitudinally of the trough to move freely therein, a plate covering said trough, an opening therein over the trough, a pin secured to each matrix bar projecting 95 vertically through said opening, a composer provided with slots as many in number as there are characters on the matrix bars, into which slots the pins are adapted to be inserted, and means for moving said composer 100 transversely across said opening and matrix bars inclosed therein, whereby the pins will be inclosed in the several slots, substantially as described.

6. The combination with a frame or bed 105 plate, of a trough therein facing upward, a plate over said trough provided with a central opening, duplicate matrix bars each provided with a consecutive series of characters formed on the lower edge thereof arranged 110 closely adjacent and longitudinally of the trough, a pin for each bar vertically projecting through said opening, and a composer for said bars provided with a corresponding number of slots to the characters in each matrix bar, in which said pins are adapted to be inserted, a slotted opening underneath the center of the composer over which the matrices are aligned, and means for justifying the matrices, substantially as described. 115

7. In combination, a trough, a plate thereon provided with a central opening, duplicate flexible matrix bars placed closely adjacent in said trough longitudinally adjustable therein, and provided each with a consecutive series of matrices in its lower edge, and with indicating characters therefor arranged to register therewith, said trough having a slot transversely across its bottom, into which the metal is injected to the matrices, 125 130

- and means for composing said matrices into line above said slot to form a printing slug, consisting of pins projecting from the upper edges of the bars, and a slotted composer 5 transversely movable across said bars and trough, substantially as described.
8. In combination with a trough, a plate thereon provided with an opening above the trough, matrix bars longitudinally movable in said trough, a pin on each bar serving as a stop for the bar against the end walls of the opening, a transverse slot in the bottom of the trough through which metal is injected to the line of the matrices, means for combining and alining the matrices above said slot, consisting of a composer arranged to move across said opening and transversely over the bars, slots in said composer in which said pins are severally inserted, and means 15 for securing the extremities of the teeth separating the slots from movement when they have passed the opening, substantially as described.
9. The combination with an elongated matrix bar provided with a series of matrices formed in one of its edges, of a combined stop and handle pin in the opposite edge, centrally placed in said bar, substantially as described.
10. In combination with a trough and matrix bars longitudinally movable therein, of a plate above said trough provided with a central opening, pins on said bars projecting through said opening, a transverse opening 25 in the bottom of the trough through which liquid metal is injected to the matrices when in alinement, a slotted composer in which the pins are assembled to aline the matrices, and means for justifying the matrix bars consisting of a stop arranged to engage the completed line of bars, and wedge shaped extremities of the said bars, substantially as described.
11. A composer for the purpose described, 30 consisting of, a toothed body portion, a supporting frame therefor having, divisions or slots between said teeth, and having a consecutive series of characters upon the extremities of the teeth, substantially as described.
12. The combination with a series of adjacent duplicate matrix bars, each bar provided with a consecutive series of matrices in its lower edge, and a corresponding series of 35 characters registering with the matrices upon its upper edge, a pin projecting from the upper edge of each matrix bar and a composer comprising a slotted plate arranged to move transversely over the bars and in the slots of 40 which the pins can be assembled and having a corresponding series of characters to those on the bars, upon the divisions between the slots of the composer, substantially as and for the purpose set forth.
13. In combination, a series of matrix bars 45 provided each with a series of matrices in its lower edge, and a corresponding series of characters on its upper edge, a pin projecting from the upper surface of each matrix bar, a slotted composer arranged to move 50 transversely over said bars, in the slots of which the said pins are adapted to be inserted, a mold box underneath the central tooth of the composer, and characters upon the teeth or divisions of the composer between 55 the slots corresponding in number and order with the characters upon the matrices, so arranged that when a pin on one of the matrix bars is inserted in the slot indicated by any one character, the corresponding matrix will 60 be located underneath the central tooth over the mold box, substantially as and for the purpose set forth.
14. A matrix bar, having duplicate & oppositely tapered extremities, substantially as 65 described and for the purpose set forth.
15. The combination with a series of adjacent reversible matrix bars, each bar having duplicate tapered extremities, of a receptacle therefor having a mold slot, in which receptacle said matrix bars are interchangeably located, substantially as described.
16. The combination with a receptacle provided with stops at both extremities, of a series of matrix bars therein, the said bars being provided with suitable projections to engage said stops.
17. The combination with a receptacle provided with stops at both extremities, and an opening in the bottom, of matrix bars therein, said matrix bars being provided with projections adapted to engage said stops, substantially as and for the purpose described.
18. The combination with a receptacle provided with stops at both extremities and an opening in the bottom, of a series of matrix bars therein, said matrix bars being provided with projections, and with wedge shaped extremities.
19. In a matrix bar, comprising a body 110 portion, and tapered extremities, a series of matrices formed in one edge thereof, recesses upon the lower edge between the matrices, wedge shaped extremities, and a projection on the edge opposite the matrices.
20. The combination with a trough provided with a narrow opening or casting slot in its bottom, of a series of matrix bars placed side by side in said trough, said bars being pointed at each end whereby the same matrices which combine to form words can be placed with their extremities overlapping to form justifiers, substantially as described.
21. The combination with a series of matrix bars, each provided with a series of matrices in one edge thereof, and wedge shaped extremities, of a receptacle for said matrices provided with an opening in its bottom, over which the matrices are alined to form words and adapted to receive the nozzle of a mold 125 130

box, the extremities of the matrices between the words being interwedged and forced together, substantially as described.

22. The combination with a receptacle provided with a large opening in its upper face and a narrow opening in its bottom adapted to receive the nozzle of a mold box, of a series of matrix bars within the receptacle provided with projections adapted to engage the walls of the said large opening in the receptacle, and limit their movement,

23. A combined justifier and matrix bar, comprising a tapered bar having matrices in the casting edge, and corresponding indicating characters in the opposite edge, the said bar being oppositely tapered at each extremity, and a central stop pin on one edge which edge has indicating characters.

24. The combination with a series of closely engaging matrix bars, each provided with a series of matrices in one edge thereof, of a slotted composing device, a mold box adjacent to said matrices and means for justifying the matrix bars consisting of the tapered and interwedged extremities of the said bars.

25. A series of duplicate matrix bars provided each with a series of matrices upon one edge thereof and means for making the matrices self justifying, consisting of tapered extremities to the matrix bars, both extremities being tapered, substantially as described.

26. In a typograph machine, the combination with a trough shaped receptacle, and cover therefor, said cover being provided with a rectangular opening, of a series of longitudinally disposed matrix bars stored in said receptacle, each of said matrix bars having a complete series of matrices in its lower surface and a vertical pin in its upper surface, and pointed extremities, a slotted composer over said matrix bars, in the slots of which said pins are inserted to compose the line, a transversely movable detent in one side of the receptacle adapted to engage the outer matrix bar and fix the width of the column, the said receptacle having a casting slot in its bottom over which said matrices are alined to form words and spaces when the pins are suitably assembled, in the composer slots, substantially as described.

27. The combination with a trough shaped receptacle provided with a casting slot in its bottom, of matrix bars longitudinally movable in said receptacle, and approximately filling said receptacle, said matrix bars being duplicates and pointed at each end, and provided each with a series of matrices on its lower edge, a pin in the upper edge of each matrix bar, a composer transversely movable across said receptacle and provided with slots in which a portion of said pins are assembled to compose said matrices in line over said casting slot, a transversely movable detent in one side of said receptacle

adapted to fix the width of the column, and matrices the pins of which are not inserted in the composer slots, and which are arranged with overlapping points to form the spaces and to justify the line, substantially as described.

28. A matrix bar comprising a body portion, a pin centrally inserted therein, on one edge, a series of matrices on the lower edge, a corresponding series of characters on the upper edge, and pointed extremities for the body portion, and grooves on the upper and lower edges between said characters and matrices, substantially as described.

29. In a typograph machine, the combination with a trough shaped receptacle, of elongated matrix bars longitudinally movable therein and provided with matrices on their lower edges, a transversely movable detent in one wall of the receptacle, adapted to fix the width of the column, and pointed extremities for said matrix bars, whereby oppositely placed bars with overlapping points can be utilized as spacers and justifiers, substantially as described.

30. The combination with a trough shaped receptacle provided with a casting slot in its bottom, and matrix bars therein, said bars being provided with transverse grooves on their upper and lower edges, of a composer, adapted to move transversely across said bars and provided with ridges adapted to engage the grooves on the upper edges of said bars, and ridges on the edges of said casting slot adapted to engage the grooves in the lower edges of said bars, substantially as described.

31. A typograph bar of elongated shape, provided with flexible pointed extremities, and with a series of matrices upon its lower surface and a corresponding series of characters upon its upper surface, a central projection upon its upper edge, and blank surfaces on the lower edge underneath said central projection and tapered extremities.

32. A series of duplicate matrix bars, provided with duplicate series of matrices, and blank spaces on their lower surfaces, and corresponding characters upon their upper surfaces, and with pointed extremities at each end, whereby said matrix bars can be employed interchangeably to form lines of letters, or spaces when arranged side by side, or to form spaces or for justifying when arranged with overlapping ends, substantially as described.

33. A matrix bar, tapering from the center toward each end, substantially as and for the purpose described.

34. A matrix bar, tapering toward each end from the center, and upon opposite sides, and provided with matrices upon one edge thereof, substantially as described.

35. A matrix bar, tapering on two sides, from the center, to each end, and provided

with matrices on one edge, and a central pin upon the other edge, substantially as described.

36. The combination with a rectangular matrix receptacle having a bottom plate and central casting slot therein, of duplicate matrix bars resting upon said bottom plate, and having duplicate pointed extremities at each end, whereby said matrix bars when arranged at each end of the receptacle, may be

brought together over the casting slot to form a line of type, the said duplicate tapered extremities being adapted interchangeably to form justifying devices for said line.

In testimony whereof I hereunto set my hand this 22nd day of December 1904.

WASHINGTON I. LUDLOW.
